LETTER AND TAPE PRINTING DEVICE

John A. Strother, Stamford, and Edwin H. Owen,
Old Greenwich, Conn., assignors to Pitney-
Bowes Postage Meter Co., Stamford, Conn., a
corporation of Delaware

Application March 9, 1940, Serial No. 323,110

7 Claims. (Cl. 101—235)

This invention relates to a machine for printing upon separate pieces of matter and upon tape at a single printing position and more particularly to means whereby the printing may be effected directly upon either the separate pieces of matter or tape without resorting to any manually selective pre-setting means.

The machine to which this invention is particularly adapted is a metered mailing machine, which prints postage stamp impressions upon letters and tape. In such machines it is now the practice to provide manually controlled selective devices whereby the machine is pre-set for the printing of either letters or tape before a printing operation is effected.

It is the principal object of this invention to provide means whereby the machine may be tripped to effect a printing operation during either a letter tripping or a tape tripping operation and to include means whereby the act of tripping during an initial tripping operation will effect movement of the tape either to a printing position or to a non-printing position.

It is another object to provide means whereby after the tape is positioned in a printing or a non-printing position during an initial tripping operation, it will continue in said position until a change in tripping occurs.

It is another object to connect a letter actuated tripping member with a tape adjusting device in such manner as to provide for the withdrawal of the tape from a printing to a non-printing position during an initial letter tripping operation and to permit further letter tripping operations without further adjustment of the tape adjusting device.

It is another object to connect a manually actuated tripping member with the tape adjusting device in such manner as to provide for the advancement of the tape to a printing position during an initial manual tripping operation and to permit further manual tripping operations without further adjustment of the tape adjusting device.

With the above and other objects in view, which will appear as the description proceeds, the invention resides in the combination and arrangement of parts and in the details of construction hereinafter described and claimed, it being understood that various changes in the precise embodiment of the invention herein disclosed may be made within the scope of what is claimed without departing from the spirit of the invention.

A preferred embodiment of the invention is illustrated in the accompanying drawings, wherein:

5 Fig. 1 is a front elevational view with parts broken away showing a portion of a metered mailing machine;

Fig. 2 is a detail side elevational view of Fig. 1 looking in the direction of the arrow 2 with parts broken away and parts in section;

10 Fig. 3 is a detail operation view showing a letter about to effect a letter tripping operation;

Fig. 4 is a detail operation view showing a letter tripping operation and the withdrawal of the tape from the printing position of Fig. 3 to a non-printing position;

15 Fig. 5 is a detail operation view showing the latter part of a cycle of operation after effecting a letter trip, with a tape retracting segment member shielded from contact with the tape as it moves to the home position of Figs. 1 and 3;

Fig. 6 is a detail operation view showing the effect of a tape tripping operation wherein the tape has been moved from a non-printing position to a printing pick-up position;

20 Fig. 7 is a detail operation view showing the position of the parts after a printing and cutting operation and with the retracting segment in a position ready to return the tape to a printing position;

30 Fig. 8 is a detail operation view showing the parts after the tape retracting member has engaged and retracted the tape to a printing position;

Fig. 9 is a modified detail operation view similar to Fig. 3 wherein a letter is about to effect a tripping operation but with a spring loaded and latch operated tape retracting member substituted for the direct operation of the retracting member by the letter trip;

40 Fig. 10 is a detail operation view similar to Fig. 9 showing a tape retracting operation to place the tape in a non-printing position, and

Fig. 11 is an enlarged perspective view of the clutch drive.

45 Referring now to the drawings in detail, the machine comprises a base portion 11 and a detachable meter unit 12, the latter containing a printing drum 13. An impression or platen roller 14 is suitably mounted upon a shaft 15, directly beneath the printing drum 13, and is adapted to be connected by means of a flexible shaft 16 to a power driven gear unit 17. The printing drum 13 is also adapted to be driven from said power drive gear 17, there being a gear 18 on a

drive shaft 19, which is connected with the printing drum 13 through gearing 21.

A one revolution clutch member is provided as generally shown at 22, Figs. 2 and 11, and includes a ratchet 23 which is an integral part of the power drive gear 17 and rotates continuously therewith about the shaft 19. Pawls 24 are pivotally mounted upon rings 25-25 and are urged toward the ratchet 23 by springs 33. Said rings 25-25 are normally supported by a clutch disc 26, one ring being cut away to provide a stop lug 27 which is normally adapted to engage the end of a clutch stop arm 28. The arm 28 is pivotally mounted on a shaft 32. The pawls 24 are normally maintained out of engagement with the ratchet 23 by means of a cam 29, pivotally mounted at 30, and having an enlarged opening 40 therein to permit rocking movement. A finger portion 31 on said cam is also adapted to normally bear against the end of the clutch stop arm 28. When said clutch stop arm 28 is rocked about its supporting shaft 32, in a manner which will be later described, the cam 29 will rock about its pivot 30 and the pawls 24 will move into contact with the ratchet 23, as a result of the force provided by springs 33, and thereby effect a drive of the shaft 19 and rotation of the printing drum through one revolution. The one revolution of the clutch is controlled by the engagement of a pin 34, on the clutch disc 26, with an arm 35, which forms a part of the clutch stop 28 on shaft 32, and thereby rocks said clutch stop 28 into the path of the stop lug 27 and cam finger 31.

During each rotation of the printing drum, a postage stamp impression will be imprinted upon either the letters or tape passed therebeneath.

Letters L may be presented for printing by hand or by means of driven belt members indicated at 39-36 which direct the letters to the printing drum 13 for printing. A suitable printing die 37 is provided in said printing drum. The tripping of the clutch 22, which effects the drive of the printing drum will be later described.

Provision is made for presenting tape T to the printing drum 13, and comprises a tape guide 38 which directs the tape to the impression roller; a tape guide 39, which directs the tape over the impression roller; and another guide 41 which both strips the tape from the platen roller 14 and cooperates with the tape guide 39 in directing the leading end of the tape to a cutting position.

In this machine the position of the tape is adjusted automatically during the initial tripping of the machine to place the machine in condition for continuous operation on the same type of article, letters or tape, without further setting changes. When it is desired to print on a different article, the initial tripping operation will reset the machine for continuous operation on the new article. These changes, during the initial tripping operation, directly control the position of the tape.

When the machine is set for printing on tape and it is desired to operate on letters, the letter passed through the machine, upon engaging the trip, will effect the retraction of the tape from a printing position before the letter approaches the printing position. When the machine is set for printing upon letters and it is desired to print upon tape, the initial trip of the manual tape trip member will effect the ad-

vancement of the tape from a non-printing position to a printing pick-up position.

The mechanism provided to accomplish the above will now be described. A letter trip finger 43 is mounted upon a shaft 44 and has an arm 45 projecting downwardly therefrom. Said arm 45 is adapted to engage a pin 46 projecting from an arm 47 of a lever 48, which lever is pivotally mounted upon a shaft 49 and further has a toe portion 51 extending sidewardly therefrom. Also fixed to the shaft 49 is a lever 52 which is linked with a lever 53 on shaft 32 by means of a link 54. A letter, upon passing between the belts or upon being moved by hand to engage the trip finger, 43 will cause the downwardly projecting arm 45 to engage the pin 46 and rock the lever 48, also the shaft 49, and through the lever and link connection 52-53 and 54, the shaft 32 is rocked. The rocking of said shaft 32 will remove the clutch stop 28 from the engagement with the stop lug 27 and finger 31 to permit a printing cycle of operation to be effected.

In a like manner a tape tripping operation is effected by means of a manual tripping lever 55, which lever is pivotally mounted upon a shaft 56 and has a sidewardly projecting arm 57 the end of which lies beneath the toe portion 51 of lever 48. When the tape trip lever 55 is actuated, the end of arm 57 will engage the toe 51 and rock the lever 48 to thereby rock the shaft 49 and effect the release of the clutch stop 28 in the same manner as that effected by the letter trip.

The control of the tape position is provided by means of a shield member 58 which is freely mounted upon a shaft 59, and has an arcuate bridge portion 61 which is adapted to pass through an opening 62 in the tape guide 38 and engage the underside of the tape. Cooperating with said shield is a presser roller 63 which is rotatably mounted upon arms 64 carried by a shaft 65. The shield 58 is directly connected to the letter trip shaft 44 through lever 66 and link 67, in such manner that when the trip lever 43 is rocked by the engagement of a letter therewith, shaft 44 will be rotated, thereby rocking the lever 66 to effect the movement of the shield 58 about the shaft 59 in a counter-clockwise direction, as shown in Fig. 4. The rocking action of said shield 58 will effect the withdrawal of the tape from the position shown in Fig. 3, as the bridge portion 61 thereof wipes across the underside of the tape opposite the presser roller 63. A flange 68 on said shield 58 has two detent slots 69-69 therein which are adapted to be engaged by a pawl 71 to thereby hold the shield in either one of two positions, the tape retracting position of Fig. 4 or a tape advancing position of Fig. 6. Said pawl is mounted upon a stud 72 and is urged against the flange 68 by means of a spring 73. It will be noted that a slotted connection is provided between the lever 66 and link 67 at 70 to permit free movement of the trip finger 43 after the initial letter tripping operation.

Assuming now that it is desired to print on tape and the last operation of the machine was for the printing of a letter. The tape lever 55 upon being struck or moved by the operator from the broken to the full line position of Fig. 6, will effect a clutch releasing and printing cycle of operation. An arm 74 fixed to the shaft 56 will be rocked with said shaft in a clockwise direction, as viewed from Figs. 1 and 6, and through the engagement of the upper end of

said arm 14 with a pin 75, projecting sidewardly from the shield 58, said shield is rocked from the position of Fig. 5 to the position of Fig. 6. During said rocking of the shield, the tape is moved thereby to the printing position, shown in Fig. 6.

After printing upon tape, the printed end of the tape is advanced between a rotary blade 76 and a stationary blade 77 of a cutting member 78, by means of which the printed portion of the tape is cut off. After a cutting operation, the leading end of the tape is returned to a printing pick-up position, Fig. 8, by means of a tape retracting segment 79 which is fixed to the shaft 59. The curved end of said segment wipes across the undersurface of the tape, opposite the position of the pressure roller 63 and drags the tape with it. Such engagement of the segment 79 with the tape is permitted only when the shield 58 is out of the path of the tape, as in the position shown in Fig. 7.

The cutting of the printed portion of the tape is effected at the end of each printing cycle of operation. The means for effecting the cutting operation comprises a lever 81 fixed to one end of the rotary cutting knife 76, which lever is connected with one end of a rocker lever 82, pivotally mounted at 83, and having a roller 84 at its opposite end which engages with a cam member 85. As the clutch shaft 19 and shaft 59 to which it is connected rotate through one revolution, the cam 85 will engage the roller 84, thereby rocking the lever 82 about the pivot 83 and effecting a rocking movement of the rotary cutter member 76. Shaft 59 is connected with the drive shaft 19 by means of a flexible shaft 80.

Instead of directly connecting the shield 58 with the trip finger 43, means is provided whereby said shield may be moved through a tape retracting operation under spring control when a latching device is tripped by the engagement of a letter with the trip finger 48. Said means is best shown in Figs. 9 and 10 and includes a spring 87 connected with a wing portion 86 projecting from the shield 58. Cooperating with said spring urged shield 58 is a latch lever 88, which is pivotally mounted upon a stud 89 and has one end thereof projecting into the path of a latch engaging member 89 on shaft 59. The opposite end of said latch lever has a pin 91 projecting therefrom which projects into the path of a trip arm 92 on shaft 44. Therefore, when the trip finger 43 is urged to the position of Fig. 10, by the engagement of a letter therewith, the trip arm 92 will engage the pin 91 and rock said latch to disengage the latching end 88 from the stop 89. The shield is thus free to be urged under spring tension to the position shown in Fig. 10 and during the rocking motion, said shield will retract the tape from the printing position of Fig. 9 to the non-printing position of Fig. 10. Resetting of the shield 58 is accomplished as previously described by the engagement of the arm 14 with the pin 75 on said shield.

Having described the invention, what is claimed is:

1. The combination with a printing machine having means for printing upon either letters or tape at a single printing point, a letter operated tripping member for initiating a machine cycle of operation for letter printing, and a manually operated tripping member for initiating a machine cycle of operation for tape printing; of means operably connected with said letter trip and operable during an initial tripping operation

thereof to effect movement of the tape from a printing position to a non-printing position, means operably connected with the manually operated trip and operable during an initial tripping operation thereof to effect movement of the tape from a non-printing to a printing position, and means to retain the tape in the position effected by the initial tripping operation so long as like tripping operations are continued.

2. In combination with a printing member and platen member, means to direct separate pieces of matter to said printing and platen members, means to direct tape to said printing and platen members, feed means to alternatively advance or retract tape to and from a printing position, tripping means to effect a printing cycle of operation for the printing of separate pieces of matter, tripping means to effect a printing cycle of operation for the printing of tape, said tripping mechanisms being operatively connected with said tape advancing or retracting means, said first tripping means being adapted to operate the feed means to retract the tape, and the second tripping means being adapted to operate the feed means to advance the tape.

3. In combination with a printing member and platen member, means to direct letters to said printing and platen members, means to direct tape to said printing and platen members, two tripping devices, one associated with letter printing and one associated with tape printing to effect alternate operation of said printing member on either letters or tape, and means operated by said tripping devices upon the initial operation of the one associated with the article to be printed upon to place the tape in a printing position when printing is to be effected upon tape or to move the tape out of a printing position when printing is to be effected upon letters.

4. In combination with a printing member and platen member, means to direct letters to said printing and platen members, means to direct tape to said printing and platen members, two tripping devices to effect alternative operation of said printing member on either letters or tape, means controlled by said tripping devices upon the initial operation of one to adjust the tape to a printing position when it is desired to print on tape or to adjust the tape out of a printing position upon the initial operation of the other tripping member when it is desired to print on letters, and means to retain the tape in either adjusted position until an initial tripping operation for a change to the printing of an article of the other type.

5. In a machine of the class described for printing upon either letters or tape, a printing member, a platen member, means to direct letters to said printing and platen members, means to direct tape to said printing and platen members, a letter operated tripping member for initiating a machine cycle of operation for letter printing, a manually operated tripping member for initiating a machine cycle of operation for tape printing, tape engaging means operatively connected with the manually operated tripping member, whereby said tape is moved from a non-printing to a printing position when the manual tripping member is actuated, spring means normally urging the tape engaging means to a tape retracting position, latch means associated with the tape engaging means to latch the tape engaging member after manual tripping is effected, and means to release said latch when initiating a letter

tripping operation to print on letters, whereby the tape engaging means is released for return by the spring to a tape retracting position and the tape is returned therewith to a non-printing position.

6. The combination with a printing machine having means for printing upon either letters or tape at a single printing point, a letter operated tripping member for initiating a machine cycle of operation for letter printing, and a manually operated tripping member for initiating a machine cycle of operation for tape printing; of means operably connected with said letter trip and operable during an initial tripping operation thereof to effect movement of the tape from a printing position to a non-printing position; and means to retain the tape in said non-printing position so long as letter printing operations are continued.

7. The combination with a printing machine having means for printing upon either letters or tape at a single printing point, a letter operated tripping member for initiating a machine cycle of operation for letter printing, and a manually operated tripping member for initiating a machine cycle of operation for tape printing; of means operably connected with the manually operated trip and operable during an initial tripping operation thereof to effect movement of the tape from a non-printing to a printing position, and means to return the leading edge of the tape to printing position in each machine cycle of operation thereafter so long as successive operations of the manual trip are continued.

JOHN A. STROTHER.
EDWIN H. OWEN.
